UNITED STATES PATENT OFFICE.

CHARLES H. FARMER, OF ASHLAND, OREGON.

AMALGAMATOR.

1,132,317.

Specification of Letters Patent. Patented Mar. 16, 1915.

Application filed September 17, 1912. Serial No. 720,872.

To all whom it may concern:

Be it known that I, CHARLES H. FARMER, a citizen of the United States, residing at Ashland, in the county of Jackson and State 5 of Oregon, have invented new and useful Improvements in Amalgamators, of which the following is a specification.

This invention relates to amalgamators and ore washers, and its object is to provide 10 a simple, reliable and efficient type of apparatus adapted for amalgamating and saving flowered quicksilver and fine and rusty gold, and which is designed to take the place of mill amalgamating plates.

15 A further object of the invention is to provide an apparatus which may be used as a placer mining washer, for the concentration of gold, silver, copper, zinc, lead and other ores, and as a settler in the separation of all 20 minerals.

The invention consists of the features of construction, combination and arrangement of parts hereinafter fully described and claimed, reference being had to the accompanying drawings, in which:—

Figure 1 is a perspective view of an amalgamator embodying my invention. Fig. 2 is a vertical section thereof. Fig. 3 is a bottom plan view of the pan. Fig. 4 is a vertical 30 section through the pan and nozzle. Fig. 5 is a similar view of the actuating crank and its bearing.

Referring to the drawing 1 designates a suitable frame structure including a floor or 35 platform 2, arranged at a suitable elevation therein, which frame or platform may be enclosed to provide a casing or housing having a door which may be locked when the apparatus is in operation, if desired.

40 Arranged in the space between the top of the frame and the platform 2 is an amalgamating, concentrating or separating pan 3 having a flat circular bottom 4 and a sloping side wall 5, preferably inclined at an angle 45 of about 30°, and secured to a carrier ring 6. In practice the pan body may be made of copper plated with silver, and may be of any size suitable for the purpose for which it is designed. The ring 6 is provided with aper- 50 tured lugs or eyes 7 engaged by the hooked lower ends 8 of a series of link rods 9, which rods have hooks or eyes 10 at their upper

ends engaging eye-bolts 11 fixed to the top bars of the frame, whereby the pan is mounted to have freedom of swinging motion in all directions as well as an oscillatory motion about its axis.

Secured to the rim 6 are the radial arms of a spider 12 which are welded or otherwise united below the center of the pan to form 60 a bearing 13. This bearing 13 is loosely engaged by a crank pin 14 carried by a crank arm 15 fixed to the upper end of a vertical power transmitting shaft 16 journaled in a bearing 17 secured to the platform 2, said 65 shaft extending through the bearing and above and below the platform. The shaft 16 revolves at a desired rate of speed and in its operation the crank pin in its orbit of movement imparts a swinging motion in all directions to the pan, by which an efficient amalgamating, washing or separating action on the contents of the pan is effected. The lower end of the pin is adjustable in a longitudinal slot 18 in the crank and provided 70 with a shoulder 19 and a threaded terminal carrying a washer 20 and clamping nut 21 whereby it may be secured in position, such adjustment permitting the throw of the crank to be varied to regulate the degree of 75 swinging motion of the pan as required. The lower end of the shaft 16 carries a bevel gear 22 meshing with a similar gear 23 on a horizontal drive shaft 24, said drive shaft being mounted in a bearing 25 and provided 80 with a cone pulley 26 whereby variable speed motion may be communicated thereto from a drive belt operated from any suitable source of power.

For the use of the device in washing ore, 90 etc., I provide above the pan 3 a water supply pipe 27 terminating at its lower end in a discharge nozzle. The said lower end of the pipe is curved downwardly to a vertical position and provided with lateral outlets 28 95 and a bottom deflector 29 to arrest the flow of the water and cause it to discharge through said outlets. Secured to and surrounding the apertured end of the pipe is an annular deflector 30 which prevents splashing of the water and directs the discharging streams of water downward against a dished spreader plate 31 supported by strips 32, said plate being of greater diameter than the

pipe and serving to distribute the water uniformly in all directions over the surface of the pan and material resting thereon, by which an efficient supply of the water to the pan is provided for.

5 The type of water discharge nozzle described is of particular efficiency for use in connection with a gyratory pan of the character disclosed, in order to insure an even discharge of the water in all directions, so that, irrespective of the direction of motion of the pan in its gyratory action, water will be uniformly supplied to the portion of the pan beneath the nozzle, while at the same 10 time gushing of the water at any point beyond the pan will be prevented or reduced to the minimum.

15 In concentrating and amalgamating, the pan is coated with quicksilver in the usual way and the pulp supplied thereto, whereby during the gyratory and up and down motions imparted thereto causes the contents to be spread over the surface thereof and rolled over and over, thus causing thorough 20 amalgamation and the separation from the air and collection of even the finest flower gold and other precious metals.

25 It will be seen from the foregoing construction that an apparatus is provided in which the pan is mounted so as to be moved freely in all directions for an efficient amalgamating, concentrating, washing or separating action, whereby the apparatus is adapted for the various uses set forth.

Brackets 33 are arranged at one side of the 35 casing and support a discharge trough 34.

I claim:

1. An apparatus of the character described comprising a suitable frame structure, a carrier ring, a pan formed of a flat 40 bottom, a rim of greater diameter than the bottom, said rim including a down-turned marginal flange fastened to said ring, and a side wall sloping at an acute angle from the flat bottom to the rim, a spider disposed beneath the ring and pan, and of a contour corresponding substantially to that of the pan, said spider having its oblique arms 45 fastened to the ring, means for suspending the pan for universal motion from the frame structure, and means connected with the spider for communicating such motion thereto.

2. In combination, a pan, means for universally swinging the same, a supply pipe 50 disposed above the pan, and provided with a nozzle having lateral discharge openings and a deflector, a casing surrounding the apertured portion of the nozzle, and a concavo-convex spreader of greater diameter 55 than the nozzle and casing.

In testimony whereof I affix my signature in presence of two witnesses.

CHARLES H. FARMER.

Witnesses:

A. O. BENNETT,
O. R. DAVIDSON.
